UNITED STATES PATENT OFFICE.

HARRY P. THOMAS, OF NEWLYN, WEST VIRGINIA.

DEVICE FOR APPLYING A LUBRICANT OR FILLER TO CABLES.

1,049,170.

Specification of Letters Patent. Patented Dec. 31, 1912.

Application filed December 27, 1910. Serial No. 599,358.

To all whom it may concern:

Be it known that I, HARRY P. THOMAS, a citizen of the United States of America, residing at Newlyn, in the county of Fayette 5 and State of West Virginia, have invented new and useful Improvements in Devices for Applying Lubricants or Fillers to Cables, of which the following is a specification.

10 I aim to provide a device of this class which is formed with a channel through which the rope passes, the passage provided by the channel having a plurality of wiping members for removing the surplus filler or 15 lubricant from the rope and adjusting the same within a pipe or receptacle having a normally closed outlet opening, the said pipe or receptacle being arranged below, and of course communicating with the passage of 20 the lubricator.

With the above and other objects in view which will appear as the description progresses, the invention resides in the novel construction and arrangement of parts here- 25 inafter fully described and claimed.

In the accompanying drawings accompanying this specification, there has been illustrated a simple and approved lubricator constructed in accordance with the present 30 invention, the showing therein, however, is to be taken as merely illustrative, as minor details of construction within the scope of the appended claims may be resorted to if desired.

35 In the drawings, Figure 1 is a perspective view of a lubricator constructed in accordance with the present invention, the sections comprising the same being illustrated in their open position. Fig. 2 is a central 40 vertical longitudinal sectional view, the sections being in their closed position. Fig. 3 is a transverse sectional view upon the line 3—3 of Fig. 2. Fig. 4 is a similar sectional view upon the line 4—4 of Fig. 2. Fig. 5 45 is a section upon the line 5—5 of Fig. 2.

In the accompanying drawings the numeral 1 designates the improved lubricator. This lubricator comprises a pair of sections designated respectively by the numerals 2 50 and 3. Each of the sections 2 and 3 are rectangular in formation and the said sections are preferably hingedly connected together as indicated by the numerals 4. Each of the sections 2 and 3 have their meeting 55 faces provided with centrally arranged longitudinally extending semi cylindrical de-

pressions 5 and 6, so that when the sections 2 and 3 are swung one upon the other, the semi cylindrical depressions form a cross sectional circular channel, as illustrated in 60 Figs. 2, 3, 4 and 5 of the drawings. The upper section 2 is provided with suitable handles 7, whereby the lubricating device may be readily removed from place to place when desired. The members 2 and 3 are 65 each formed with suitable securing elements designated by the numerals 8 and 9 whereby the said members 2 and 3 may be securely locked when in their closed position. The securing elements 8 and 9 may be of any 70 desired or preferred structure, but the said elements preferably comprise winged bolts, each of the same being adapted to enter threaded orifices in the opposite section. By this arrangement it will be noted that when 75 the members 2 and 3 are closed the winged bolts 8 and 9 effectively and securely retain the sections one upon the other. It will be further noted that, should the occasion demand, the said sections may be sustained in 80 an adjusted position one in relation to the other.

The upper section 2 is formed, adjacent one of its ends with an opening 10 which communicates with the channel formed by 85 the members 2 and 3. This opening is adapted for the reception of the spout of a suitable hopper 12, the said hopper being adapted to receive the lubricant or filler which is delivered to the central channel of 90 the lubricator. The opening 10 has its walls preferably inclined and toward the outer face of the ends of the sections 2 and 3, so that the lubricant will be guided toward the end of the cable 13 which first enters the 95 channel.

The numeral 14 designates a wiper which is arranged adjacent the opening 8 and which extends within the channel of the device. 100

The forward or opposite end of the member 2, to that occupied by the hopper 12 is formed with a pair of spaced depressions 15, the latter being adapted for the reception of wiping members 16. Communicating with the depressions 15 are threaded openings 17, the same being adapted for the reception of threaded headed elements 18. The inner extremities of each of the inner members 18 is formed with a ball head 19 and 110 each of the said heads is adapted to be received within a suitable circular opening 20

2

provided within the offsets formed upon the wiper holding members 21. Each of the said members 21 is substantially U-shaped in cross section, and the side arms of the 5 said members have their upper extremities bent inwardly to form the substantially continuous teeth 22. These teeth 22 are adapted to engage the opposite sides of the wipers 16 adjacent the lower ends thereof.

10 The lower section 3 is formed with coinciding depressions arranged adjacent the depressions 15. These depressions, designated by the numeral 23, are also adapted for the reception of wiper members 24. The member or section 3 is formed with threaded openings communicating with the depressions, and the said openings are adapted for the reception of threaded headed elements 25. These elements are similar to the elements 18 and the wiper holding elements 26 are also similar to the wiper holding elements 21. The section 3 directly opposite the wiper 14 is also provided with a depression adapted for the reception of a suitable 25 wiper, and this wiper is vertically adjustable through the medium of the element 27. The method of sustaining and retaining the wiper 28 is similar to that of the wipers hereinbefore described.

30 The numeral 29 designates, what I term, the storage tube or pipe of the lubricator. This pipe 29 extends longitudinally below the lower section 3 and communicates therewith and with the central chamber directly 35 opposite the threaded element 27, as clearly illustrated in Fig. 2 of the drawings, while the opposite end of the said member has its outer wall connected between the wiper members 24. The space between the wipers 40 and the longitudinal channel is provided with an opening 30 so that the lubricant within the channel and between the wipers will receive free access to the pipe 29.

The numeral 31 designates an auxiliary pipe. 45 This pipe communicates with the longitudinal channel directly below the inner wiper member 24 which is arranged farthest within the channel so that the lubricant scraped from the said cable by the wipers 16 and 24 50 may be free to pass to the pipe 29.

Connected with the pipe 29 adjacent the point of communication of the said pipe with the rope entrance end of the lubricator is a drain cock 32. This cock is for use in 55 draining off the lubricant after all of the cable has passed through the lubricator.

Having thus fully described the invention, what I claim as new, is:—

1. In a lubricator of the class set forth, a

pair of rectangular members hingedly secured together, each of said members having their opposite faces provided with threaded depressions, the opposite faces of each of the members being further provided with headed threaded elements adapted to coact with the said threaded depressions, the meeting faces of each of the said sections being formed with longitudinally extending semicylindrical depressions, one of the said members being formed with a lubricant opening adjacent one of its ends, the said section being further provided with an inclined wiper member which communicates with the semicylindrical depression, the opposite end of the said member being formed with spaced depressions, wiper members for the said depressions, threaded adjusting members engaging the wipers, the lower section being provided with depressions coinciding with the depressions of the first named section, wiper members in each of said depressions, threaded adjusting members for each of the wipers, a pipe for the second section, said pipe having its opposite ends secured to the said second section between the spaced wiper members adjacent one of the ends of the lubricator and adjacent the wiper member arranged at the opposite end of the lubricator, and an auxiliary pipe member communicating with the channel formed by the semicylindrical depressions and the pipe member, substantially as and for the purpose set forth.

2. A lubricating device, for the purpose set forth comprising a pair of hinged members each formed with a centrally arranged longitudinally extending semi-cylindrical channel, means provided upon both of the members for locking the members together, one of the said members being provided with a lubricant entrance opening which is arranged adjacent one of its ends, both of the members being provided with a plurality of oppositely arranged adjustable wipers which project with the channel, one of the members being provided with a plurality of openings which are arranged adjacent its wipers, a pipe provided with an outlet cock disposed below this member and the said pipe communicating with all of the openings of the last named member.

In testimony whereof I affix my signature in presence of two witnesses.

HARRY P. THOMAS.
